UNITED STATES PATENT OFFICE.

ROBERT A. GALLY, OF CINCINNATI, OHIO, ASSIGNOR TO THE BALDWIN COMPANY, OF CINCINNATI, OHIO.

MUSIC-PLAYER STICKER-ACTION.

1,275,181.

Specification of Letters Patent.

Patented Aug. 6, 1918.

Application filed August 8, 1917. Serial No. 185,161.

To all whom it may concern:

Be it known that I, ROBERT A. GALLY, a citizen of the United States, and residing at Cincinnati, in the county of Hamilton and 5 State of Ohio, have invented certain new and useful Improvements in Music-Player Sticker-Action, of which the following is a specification.

In prior structures for the pneumatic 10 striker operation of pianos and the like, sticker actions with stacks of pneumatics, etc., have been employed, but these have been difficult to regulate, especially when situated under the keybed of grand or other pianos, 15 as it has been necessary to reach and regulate nuts or buttons at upper and lower positions of the stickers, while in the present invention it is easy to regulate both the leveling of the sticker to the key or other instrument 20 action actuator or member, and also the amount of the stroke of the striker pneumatic and its sticker and the key or other member actuated by the said pneumatic, and sticker, such regulation being accomplished by turning 25 the sticker from its lower end for the stroke regulation, and turning the leveling button at the lower end of the same sticker for the leveling of the sticker to the said key or similar part. The present showing is 30 as applied to a grand piano, only one of the three rows of striker pneumatics being shown, although it is to be understood that several rows are employed, in any suitable arrangement, the sticker being made sufficiently long for such purpose, the one shown 35 in the present drawings being broken apart for economy of space in the drawing.

In the drawings Figure 1 is an end view 40 of the keys of a piano, with the keybed there- with cut in section to exhibit the player sticker and the guide rail therewith at the upper end of the stickers, a striker pneumatic and regulators being shown below; Fig. 2 is a rear elevation of the same parts 45 taken on the line A of Fig. 1, with the rear guard of the guide rail of the stickers removed to show the detail of one of the leveling buttons of the stickers; and Fig. 3 is a plan view of one of the striker pneumatics 50 and its lever arm and the sticker with its stroke regulator.

Manual keys 1 are shown supported on the usual keybed 2, it being understood that although only one key is now shown, any 55 required number are employed. Under the

rear end of the key 1 is the striker button 3 carried by the upper end of the vertical sticker 4, the button 3 raising the said rear end of the key 1 to actuate the musical devices controlled by that key whenever said 60 button 3 and sticker 4 are thrust upward by the operation of the striker pneumatic 5, which striker pneumatic 5 has a lever arm 6 fixed therewith and extended beyond the heel of the said pneumatic and engaging a 65 nut 7 on the said sticker 4 to accomplish the said stroke.

The nut 7 has a hole tapped through it to fit the raised threads 8 on the sticker wire 4, and one end of an element or strap 9 70 is fixed to the said nut 7 and the other end of said strap 9 is loosely attached to a distant part of the lever arm 6 or the pneumatic 5, so that the strap 9 will prevent the turning 75 of the nut 7 when the sticker 4 is turned 80 to regulate the vertical position of the sticker 4 relatively to its nut 7, thus enabling such regulating by a handling of the sticker only, and at any convenient part of the sticker, as the lower end, and such regulating not requiring any touching or gripping of the nut 7 as is used in regulating of stickers to their nuts or buttons. It is preferable that the strap 9 be of a flexible nature, as shown to allow the free movement of the rod 85 or sticker 4.

Inside the striker pneumatic 5 is a pad or check 10 of felt or other noiseless material for checking purposes, and the movement of the striker pneumatic 5 is limited by this 90 check as the moving board 11 of the pneumatic 5 reaches the said check 10 similarly to the old organ pneumatic checks, as in Odell #609,291. Thus by the regulating of the vertical position of the nut 7 on the 95 thread 8 of the sticker 4, the exact limit of the stroke of the key 1 can be secured.

To prevent any lost motion between the start of the stroke of the pneumatic 5 and the rise of the sticker 4 and its button 3 to 100 the key 1, a leveling button 12 is threaded on to the threads 13 at the lower end of the sticker 4, and the stickers 4 are thus held up to position by a felted bearing or rest 14 on a leveling rail or support 15. To secure an 105 exact relation between the striker button 3 of the sticker 4 to the key 1, the sticker 4 may be held by pliers against turning in its nut 7, and the leveling button 12 be then regulated up or down on the threads 13 of 110

the sticker 4 until the button 3 has the desired touch or clearance relative to the lower face of the rear of the key 1. To enable the regulating of the stroke limit after the leveling of the button 3 to the key 1, it is preferable to have the nut 7 with a fairly free turning fit to the threading 8 of sticker 4 compared to a fairly snug fit of the leveler button 12 to the threads 13 of the same sticker 4 as by a sole leather inset 16, so that after the said leveling of the striker button 3, the leveler button 12 can be grasped by the finger and thumb and the sticker 4 turned in the nut 7 without disturbing the setting of the leveler button 12 on the sticker 4.

To prevent the accidental turning of the stickers 4 in their nuts 7, the leveling rail or support 15 has a flange or guide strip 17 disposed to one side of the line of stickers 4 and their leveler buttons 12, and so close to the said leveler buttons 12 that the said buttons will not be turned by the operating motion of the buttons 12 and the stickers 4, but can only be turned when a mechanic pulls them sufficiently away from the said guide 17 and its anti-friction facing 18 to enable the turning of such a button 12 on its sticker 4 for leveling a striker button 3, or for turning the button 12 and its sticker 4 together as one when regulating the said sticker 4 in its nut 7 for limiting the stroke of the pneumatic 5, sticker 4, striker button 3 and the key 1.

As an additional safeguard against the accidental turning of the leveler button 12 and the stickers 4, an extra guard 19 may be removably attached to the main support 15 as shown in Fig. 1, such extra guard 19 being removed during any regulating work with the buttons 12 and stickers 4 as shown in Fig. 2, where said extra guard 19 has been removed.

It is desirable to have the leveler button 12 of flat form to insure the guards 17 and 19, or guard 17 only, if only the one is used, against the turning of the button 12, and best that the said button 12 be of greater width than thickness, whereby is obtained the greatest possible control against turning, the relative measure of both the width and diagonal and horizontal measures of the buttons 12 being of a greater ratio to the thickness than in a square section body, and the angle of both the width face and the diagonal of the corners being nearer to parallel with the faces of the guides 15 or 19 than if the button 12 were of square section.

The leveling rail or support 15 may be either set to a fixed position or be vertically adjustable by any means as the screws 20 in any fixed part of the apparatus as 21.

While the guides 17 and 19 prevent any motion of the stickers 4 lengthwise of the levers 6, any motion in direction of the length of the guide 17 must be prevented,

and to do this by having the stickers engage the levers 6, through a small hole in the said levers would cause a cramping from the arc of motion of the hinged lever arms 6 against the straight line of motion of the said stickers 4 as controlled by the buttons 12 between guides 17 and 19 and the guide rail 22 guiding the upper ends of the stickers, therefore each lever arm 6 has an opening or slot 23 elongated in the direction of the length of the said lever 6 and through which said opening the sticker 4 extends.

Although the heel lever type of pneumatic may be used with the regulators, etc., as shown herein, the regulators, nuts, straps and leveling devices of the present invention are adaptable to any other arrangement of striker pneumatics and levers in any so called action of "stack" where convenient leveling, regulating, and checking or limiting is desired, and the use of a horizontal heel lever pneumatic combined with a sticker under the keys is a particular matter of claims in this applicant's separate application, #184,355, filed Aug. 3, 1917.

What I claim as my invention is:—

1. A musical apparatus sticker and means connected with and actuating said sticker longitudinally; a nut on said sticker engaged therewith by screw threads adapted for the regulation of said nut lengthwise of the said sticker, and an actuating element of the apparatus engaging the said nut and a flexible element having one of its ends attached to the said nut, the other end of the said element attached to an element of the apparatus other than said nut or sticker and adapted to prevent the revolution of the said nut.

2. A musical apparatus sticker and means connected with and actuating said sticker longitudinally; a nut on said sticker engaged therewith by screw threads adapted for the regulation of said nut lengthwise of the said sticker, and an actuating element of the apparatus engaging the said nut and an element having one of its ends attached to the said nut, the other end of the said element loosely attached to an element of the apparatus other than said nut or sticker, and adapted to prevent the revolution of the said nut.

3. A musical apparatus sticker and means connected with and actuating said sticker longitudinally; a nut on said sticker engaged therewith by screw threads adapted for the regulation of said nut lengthwise of the said sticker, and a flexible element having one of its ends attached to the said nut, the other end of the said strap attached to an element of the apparatus other than said nut or sticker and adapted to prevent the revolution of the said nut.

4. A musical apparatus sticker and means connected with and actuating said sticker

longitudinally; a nut on said sticker engaged therewith by screw threads adapted for the regulation of said nut lengthwise the said sticker, and an actuating element of 5 the apparatus engaging the said nut and a flexible strap having one of its ends attached to the said nut, the other end of the said flexible element loosely attached to an element of the apparatus other than said nut 10 or sticker and adapted to prevent the revolution of said nut.

5. A hinged striker pneumatic having a moving board and a lever fixed to said moving board and extended beyond the said 15 hinge and having an arc-like movement of its said extended part; a sticker extended through the extended end of the said lever; a nut on the said sticker engaged therewith by screw threads and adapted for the regulation 20 of the said nut lengthwise of the said sticker to and away from the said lever; and an actuating element of the apparatus engaging the said nut and an element having one of its ends attached to the said nut and 25 its other end loosely attached to a moving part of the said pneumatic.

6. A hinged striker pneumatic having a moving board and a lever fixed to said moving board and extended beyond the said 30 hinges and having an arc-like movement of its said extended part; a sticker extended through the extended end of the said lever; a nut on the said sticker engaged therewith by screw threads and adapted for the regulation 35 of the said nut lengthwise of the said sticker to and away from the said lever; and an actuating element of the apparatus engaging the said nut and a flexible element having one of its ends attached to 40 the said nut and its other end attached to a moving part of the said pneumatic.

7. A hinged striker pneumatic having a moving board and a lever fixed to said moving board and extended beyond the said 45 hinge and having an arc-like movement of its said extended part; a sticker extended through the extended end of the said lever; a nut on the said sticker engaged therewith by screw threads and adapted for the regulation 50 of the said nut lengthwise of the said sticker to and away from the said lever; and an actuating element of the apparatus engaging the said nut and a flexible element having one of its ends attached to the said 55 nut and its other end loosely attached to the said lever of the said pneumatic.

8. A vertical sticker having its upper end adapted to actuate a movable member of a musical apparatus; an actuating means engaging the said sticker intermediate its 60 length and adapted to actuate said sticker vertically; a leveling support immediately below the lower end of the said sticker, screw threads at the lower end of the said sticker and a leveling button 65 and a leveling button on the lower end of

said sticker and engaged by the said threads and adjustable thereon vertically of the said sticker; the lower end of the said button resting on the said leveling support.

9. A vertical sticker having its upper end 70 adapted to actuate a movable member of a musical apparatus; an actuating means engaging the said sticker intermediate its length and adapted to actuate said sticker vertically; a leveling support immediately below the lower end of the said sticker, screw threads at the lower end of the said sticker and a leveling button on the lower end of the said sticker and engaged by the said threads and adjustable thereon vertically 80 of the said sticker; the lower end of the said button resting on the said leveling support, and means adapted to raise and lower the said leveling support.

10. A vertical sticker having its upper end 85 adapted to actuate a movable member of a musical apparatus; a striker pneumatic having an actuating means engaging the said sticker intermediate its length and adapted to actuate said sticker vertically; a leveling 90 support immediately below the lower end of the said sticker, screw threads at the lower end of the said sticker and a leveling button on the lower end of said sticker and engaged by the said threads and adjustable thereon 95 vertically of the said sticker; the lower end of the said button resting on the said leveling support.

11. A vertical sticker having its upper end adapted to actuate a movable member 100 of a musical apparatus; a striker pneumatic having an actuating means engaging the said sticker intermediate its length and adapted to actuate said sticker vertically; a leveling support immediately below the lower end of 105 the said sticker, screw threads at the lower end of the said sticker and a leveling button on the lower end of the said sticker and engaged by the said threads and adjustable thereon 110 vertically of the said sticker; the lower end of the said button resting on the said leveling support; and a regulating means on the said sticker and adjustable lengthwise thereof and adapted to contact with the said actuating means of the said 115 striker pneumatic.

12. A vertical sticker having its upper end adapted to actuate a movable member of a musical apparatus; a striker pneumatic having an actuating means engaging the said 120 sticker intermediate its length and adapted to actuate said sticker vertically; a leveling support immediately below the lower end of the said sticker, screw threads at the lower end of the said sticker and a leveling button 125 on the lower end of said sticker and engaged by the said threads and adjustable thereon vertically of the said sticker; the lower end of the said button resting on the said leveling support; a screw thread on and inter- 130

- mediate the length of the said sticker, and a nut engaged by said screw thread and adjustable vertically of the said sticker adjacent to and engaging the said actuating means.
13. A vertical sticker having its upper end adapted to actuate a movable member of a musical apparatus; a screw thread on and intermediate the length of the said sticker, and a nut engaged by said screw thread and adjustable vertically of the said sticker; a striker pneumatic, and a means actuated thereby adjacent to and engaging the said nut; and an element having one end thereof attached to the said nut and its other end attached to said actuating means to prevent the revolution of the said nut.
14. A vertical sticker having its upper end adapted to actuate a movable member of a musical apparatus; a screw thread on and intermediate the length of the said sticker, and a nut engaged by said screw thread and adjustable vertically of the said sticker; a striker pneumatic, and a means actuated thereby adjacent to and engaging the said nut; and an element having one end thereof attached to the said nut and adapted to prevent the revolution of the said nut, and its other end attached to a part of the apparatus other than the said nut or sticker to prevent the revolution of the said nut.
15. A vertical sticker having its upper end adapted to actuate a movable member of a musical apparatus; a striker pneumatic having a moving board hinged at one end thereof and a lever fixed to the said moving board and extended beyond the said hinge, the said extended part of the said lever engaging the said sticker intermediate its length and adapted to actuate said sticker vertically; a leveling support immediately below the lower end of the said sticker, screw threads at the lower end of the said sticker and a leveling button on the lower end of the said sticker and engaged by the said threads and adjustable thereon vertically of the said sticker; the lower end of the said button resting on the said leveling support; a screw thread on and intermediate the length of the said sticker, and a nut engaged by said screw thread and adjustable vertically of the said sticker adjacent to and engaging the said actuating means.
16. A vertical sticker having its upper end adapted to actuate a movable member of a musical apparatus; screw thread on and intermediate the length of the said sticker, and a nut engaged by said screw thread and adjustable vertically of the said sticker; a striker pneumatic, and a means actuated thereby adjacent to and engaging the said nut, and a flexible element having one end thereof attached to the said nut and its other end attached to said actuating means to prevent the revolution of the said nut.
17. A vertical sticker having its upper end adapted to actuate a movable member of a musical apparatus; a screw thread on and intermediate the length of the said sticker, and a nut engaged by said screw thread and adjustable vertically of the said sticker; a striker pneumatic, and a means actuated thereby adjacent to and engaging the said nut, and a flexible element having one end thereof attached to the said nut and its other end attached to a part of the apparatus other than the said nut or sticker and adapted to prevent the revolution of the said nut.
18. A sticker; screw threads on the said sticker at one end thereof, and a rectangular regulating button on the same said end of the said sticker and engaged by the said threads, and a guide member having a flat face adjacent to and parallel with one face of the said button and adapted to prevent the turning of the said button.
19. A sticker adapted to be actuated longitudinally of itself having its one end adapted to actuate a movable member of a musical apparatus; a guide in which the said sticker is guided near the same said end of the said sticker; a guide means at the other end of the sticker; an engaging means on an intermediate part of the sticker; a pneumatic lever positioned transversely of the said sticker and engaging the said engaging means, the part of said lever so engaging the said means having an elongated opening through which the said sticker extends.
20. A sticker having one end adapted to actuate a movable member of a musical apparatus; a screw thread on and intermediate the length of the said sticker, and a nut engaged by said screw thread and adjustable vertically of the said sticker; a striker pneumatic, and means actuated thereby adjacent to and engaging the said nut; and an element having one end thereof attached to the said nut and its other end attached to said actuated means to prevent the revolution of the said nut.
21. A sticker having one end adapted to actuate a movable member of a musical apparatus; a screw thread on and intermediate the length of the said sticker, and a nut engaged by said screw thread and adjustable vertically of the said sticker; a striker pneumatic, and means actuated thereby and adjacent to and engaging the said nut; and an element having one end thereof attached to the said nut to prevent the revolution of the said nut, and its other end attached to a part of the apparatus other than the said nut or sticker to prevent the revolution of the said nut.
22. A sticker having one end adapted to actuate a movable member of a musical apparatus; a screw thread on and intermediate

- ate the length of the said sticker, and a nut engaged by said screw thread and adjustable vertically of the said sticker; a striker pneumatic, and a means actuated thereby and 5 engaging the said nut; and a flexible element having one end thereof attached to the said nut and its other end attached to said actuated means to prevent the revolution of the said nut.
- 10 23. A sticker having one end adapted to actuate a movable member of a musical apparatus; a screw thread on and intermediate the length of the said sticker, and a nut engaged by said screw thread and adjustable 15 vertically of the said sticker; a striker pneumatic and a means actuated thereby and adjacent to and engaging the said nut; and a flexible element having one end thereof attached to the said nut and its other end 20 attached to a part of the apparatus other than the said nut or sticker and adapted to prevent the revolution of the said nut.
24. An actuating rod movable longitudinally of its main axis; a screw thread on 25 and intermediate the length of the said rod, and a nut engaged by said screw thread and adjustable longitudinally of the said rod; a striker pneumatic, and means actuated thereby adjacent to and engaging the said 30 nut; and an element having one end thereof attached to the said nut and its other end attached to said actuated means to prevent the revolution of the said nut.
25. An actuating rod movable longitudinally of its main axis; a screw thread on 35 and intermediate the length of the said rod, and a nut engaged by said screw thread and adjustable longitudinally of the said rod; a striker pneumatic, and means actuated thereby adjacent to and engaging the said 40 nut; and an element having one end thereof attached to the said nut to prevent the revolution of the said nut, and its other end attached to a part of the apparatus other 45 than the said nut or rod to prevent the revolution of the said nut.
26. An actuating rod movable longitudinally of its main axis; a screw thread on 50 and intermediate the length of the said rod, and a nut engaged by said screw thread and adjustable longitudinally of the said rod; a striker pneumatic, and means actuated thereby adjacent to and engaging the said 55 nut; and a flexible element having one end thereof attached to the said nut and its other end attached to said actuated means to prevent the revolution of the said nut.
27. An actuating rod movable longitudinally of its main axis; a screw thread on 60 and intermediate the length of the said rod, and a nut engaged by said screw thread and adjustable longitudinally of the said rod; a striker pneumatic, and means actuated thereby adjacent to and engaging the said 65 nut; and a flexible element having one end thereof attached to the said nut to prevent the revolution of the said nut, and its other end attached to a part of the apparatus other than the said nut or rod to prevent the revolution of the said nut.
28. A hinged striker pneumatic having a moving board and a lever fixed to said moving board and extended beyond the said hinge and having an arc-like movement of its said extended part; a sticker extended 75 through the extended end of the said lever; a nut on the said sticker engaged therewith by screw threads and adapted for the regulation of the said nut lengthwise of the said sticker to and away from the said lever; 80 and a flexible element having one of its ends attached to the said nut and its other end attached to an oscillating part of the said pneumatic.
29. A hinged striker pneumatic having a moving board and a lever fixed to said moving board and extended beyond the said hinge and having an arc-like movement of its said extended part; a sticker extended through the extended end of the said lever; 85 a nut on the said sticker engaged therewith by screw threads and adapted for the regulation of the said nut lengthwise of the said sticker to and away from the said lever; 90 and a flexible element having one of its ends attached to the said nut and its other end attached to an oscillating part of the said lever.
30. A vertical sticker having its upper end adapted to actuate a movable member of a musical apparatus; an actuating means engaging the said sticker intermediate its length and adapted to actuate said sticker vertically; a leveling support immediately below the lower end of the said sticker, and 95 a leveling means on the lower end of said sticker and adjustable thereon vertically of the said sticker; the lower end of said leveling means resting on the said leveling support.
